DESK LOCK

Benjamin G. Rand, North Tonawanda, N. Y.,
assignor to Remington Rand Inc., Buffalo,
N. Y.

Application April 22, 1930. Serial No. 446,342

5 Claims. (Cl. 45—94)

This invention relates to a locking mechanism for desks or similar furniture wherein the locking of a number of drawers is controlled by a single means.

- 5 Locking mechanisms now in use on the pedestal types of office desk are usually controlled from the central drawer which contains or actuates suitable mechanism to simultaneously lock or unlock all of the drawers of a desk. This invention 10 particularly comprehends improvements in locking mechanisms which are controlled by the lock of the central drawer and concerns the provision of a simple mechanism characterized by its easy accessibility for repair and in its small number 15 of parts in which the use of springs has been entirely eliminated. This has been accomplished by providing a center drawer lock, which acts to directly lock all the drawers when in a locked position and to pre-set the pedestal drawers for 20 automatic unlocking when in an unlocked position. This principle of operation has permitted an extremely simple structure which is more fully described in the specification and the accompanying drawing.

25 In the drawing:

Fig. 1 is a fragmentary front elevation of the drawer locking mechanism in which the desk structure is shown in phantom view.

Fig. 2 is a section on the line 2—2 of Fig. 1.

30 Fig. 3 is a rear elevation of the lock of the central drawer.

Fig. 4 is a section taken substantially on the line 4—4 of Fig. 2 with portions omitted for convenience in illustration.

35 Fig. 5 is a section on the line 5—5 of Fig. 3.

In the specification the numeral 1 indicates a conventional type of desk equipped with a top 2, pedestals 3 having drawers 4 therein, and a central drawer 5. For convenience of illustration 40 the desk is shown of a sheet metal construction, although it will be understood that the locking principle hereinafter disclosed may be utilized on any type of desk or equipment in which the locking of drawers is concerned. The desk shown

45 is provided with outer leg members 6 and inner leg members 7. The outer and inner leg members on each pedestal are secured thereto by sheet metal panelling and the usual cross members.

Thus, the inner leg members are connected from 50 front to rear by a partition 8, (Fig. 2), which is provided with inturned flanges 9 at its upper and lower edges and is secured to a Z-shape member 10 which partially embraces the inner legs and is secured thereto.

55 The drawers 4 of the pedestal are slidably

mounted therein in spaced relation to said partition. The central drawer 5 is similarly mounted and extends between the inner legs 7. The front of the central drawer is equipped with a tubular sleeve 12 which is shouldered at 13 and extends 60 through the front of the drawer, and is rotatably mounted therein. The end of the sleeve within the drawer is slotted at 14 for purposes hereinafter described, and also contains a concentric bore 15 and a counterbored portion at one extremity of said bore. The sleeve is also provided with a depending handle 17 which extends downwardly from the protruding portion thereof. The bore of the sleeve is adapted to receive and retain a lock 18, comprising a barrel 19 having a key slot 70 19' and an enlarged shoulder portion 20 which engages the counterbore portion of the sleeve, thus preventing outward removal of the lock.

The inner end of the lock is provided with a pin 21 which protrudes therefrom and extends 75 through the vertical slot 22 of the rectangular bolt 23 which is slidably mounted within the slot 14 of the sleeve 12. The bolt is retained in said slot by a cover member 25 which is secured over the slot of the sleeve by the screws 26. 80 These screws also secure the bearing plate 27 to the cover member. The bearing plate is a rectangular member having a lip portion 28 extending from either side thereof and having a stud 29 riveted thereto in the central portion 85 thereof. The stud 29 acts as a rear bearing member for the entire lock assembly by being received by the bearing panel 30 of the lock housing. The lock housing is a sheet metal stamping secured to the back of the drawer and 90 having at top and bottom extending supporting portions 31 which extend beyond the lock assembly and contain aligned slots 32. The bearing panel previously described contains offset end portions which enter such slots and are prevented from removal therefrom by the pin 33 which extends through the projecting portion of the stud 29. The housing is also provided with a side leg 35 containing a lock slot 36 in horizontal alignment with the bolt 23 of the lock. 100

As shown in Fig. 3, when the sleeve is turned by actuation of the handle 17 the entire lock assembly is carried with it and rotates within the housing to the position shown in dotted lines at 37. When it is desired to lock this assembly 105 against such rotation, the handle is moved to its perpendicular position and the key is inserted in the lock 18 which is turned, thus moving the pin 21 to its position to the right, (Fig. 2), and simultaneously actuating the bolt 23 for move- 110

ment to the right where it enters into the slot 36 of the housing, thus preventing arcuate movement of the lock assembly.

The rod 38 having a bifurcated end 39 provided with alinged openings is pivotally attached to each of the lip portions of the plate 27 by the rivets 40. The other end of each rod projects through opposite sides of the drawer through suitable apertures 41 and the projecting end is beveled at 42. Thus, when the handle of the lock is turned, the rods 38 are either simultaneously withdrawn to the position shown in dotted lines of Figure 2 at 43 or extended to the position indicated in full lines of such view. These rods act as locking bolts for the central drawer and also as actuators for the pedestal drawer locking standard hereinafter described.

The drawers in each pedestal are provided with a single locking mechanism which comprises a standard or locking bar 45 which is mounted vertically in each pedestal between the flanges 9 of the inner partition. This member is adapted for rotary movement and is journalled in the journal boxes 46 and 47 which are secured to the upper end lower flanges of the inner panels. Locking fingers 48 are attached to the standard and extend laterally therefrom at spaced intervals. These members are preferably of heavy sheet metal and are secured within the recess portions 49 of the standard and extend toward the drawers. A lever arm 50 is attached to the standard near its upper extremity and extends at substantially right angles to the locking fingers and is provided with a hole 51 near its free end. The opposite side of the inner panel is provided with a horizontally arranged bracket 52 upon which is mounted a bell crank 53 by the stud 54. The arm 55 of the bell crank is cut away at 56 to fit around the corner of the leg 7 for limited movement and is slotted at its opposite edge at 57, the slot being in alignment with the previously described rod 38.

The other arm 58 of the bell crank is curved and extends through an orifice 59 stamped out of the inner partition and projects therethrough in close proximity to the lever 50 and contains a hole 60 at its extremity. The arm 58 and the lever 50 are connected by a link 61 containing depending portions 62 which enter upon and are secured through the holes of each member. The bell crank is adapted for slight horizontal angular movement as shown in Figure 2 from the dotted position therein indicated to the position shown in full lines. Upon such movement the bell crank will actuate the standard for a rotary movement of about 30° as shown at 63.

The inner side wall of each pedestal drawer is provided with a spring dog 65 which is arranged in position opposite the locking fingers. These members have sufficient resiliency so that when the drawer is moved from an open position to a closed position, the end of the spring dogs will slide under the locking fingers and then spring open to a locking position.

In operation, when the lock is secured and the drawers are closed, an inter-connected locking mechanism results wherein the locked rods 38 are in their extended position and are received in the slot 57 in the arm 55 of the bell crank. The opposite arm 58 of the bell crank through the link 61 prevents counter-clockwise movement of the standard whereby upon any pull on any of the pedestal drawers, the dogs 65 by engaging upon the locking flanges are prevented from re-

moval from the pedestal. Should the central drawer be closed and locked, the drawers of the pedestal can be pushed into locked position as the dogs 65 are flexible and the extending portion thereof may flex under the fingers 48 as previously described.

When the central drawer is unlocked and the handle turned to the open position the bell crank lever is thereby free to move in a counter-clockwise direction and is pre-set for unlocking. Actuation of any one of the pedestal drawers subsequent to this operation will result in its spring dog 65 turning the standard in a counter-clockwise direction and carrying the bell crank lever with it to an unlocked position.

What is claimed is:

1. In a desk drawer lock, the combination with a desk having a plurality of drawers arranged in a pedestal, and a center drawer adjacent said pedestal, of a locking bar rotatably mounted in said pedestal and having laterally extending fingers attached thereto, a handle on said central drawer, a rod operatively connected thereto for outward movement through the side of said drawer, a bell crank lever rotatably mounted on the desk and actuated by said rod, and means connecting said bell crank lever with said locking bar whereby upon actuation of said bell crank lever said locking bar will be rotated to a locked position, and dogs attached to said pedestal drawers and engaging said fingers on said locking bar when said locking bar is in a locked position.

2. In a desk drawer lock, the combination with a desk having a plurality of drawers arranged in a pedestal, of a rotatable locking bar vertically mounted adjacent said drawer within said pedestal and adapted for rotary movement, spaced rigid fingers attached thereto, dogs on said drawers arranged opposite said fingers, each dog comprising a strip member secured to a drawer and having a resilient portion extending therefrom to contact with a finger, and means for locking said bar in a fixed position.

3. In a desk drawer lock, the combination with a desk having a plurality of pedestal drawers and a central drawer, of a locking mechanism for said pedestal drawers comprising a rotatable locking bar mounted in said pedestal and having laterally extending fingers thereon, a rod extending through said central drawer, means on said central drawer for selectively moving said rod to one of two positions, means connecting said rod to said locking bar for actuation thereof to a fixed position, and dogs upon said pedestal drawers adapted to engage said fingers on said locking bar when said locking bar is in a fixed position.

4. In a desk drawer lock, the combination with a desk having a plurality of pedestal drawers and a central drawer, of a rotatable locking bar mounted adjacent said pedestal drawers and having laterally extending fingers thereon, a spring dog on each of said pedestal drawers adapted for engagement with said fingers on said locking bar when said locking bar is in a locked position, a lever on said locking bar, a bell crank on said pedestal having one arm attached to said lever, independent locking means for said central drawer, a rod adapted for actuation by said independent locking means and extending through the side of said central drawer and engaging the remaining end of said bell crank lever to move the same, whereby upon movement of said

bell crank lever said rotatable locking bar will be turned to a locked position.

5. In a drawer lock, the combination with a housing having a plurality of drawers, of a locking bar for said drawers having laterally extending rigid fingers thereon, locking dogs comprising a resilient member secured to each drawer, means for operating said locking bar to move the fingers thereof in the path of the dogs for locking co-

operation therewith, said drawers being adapted to be closed when the locking bar is in locked position, said resilient dogs engaging said rigid fingers during such closing operation and being cammed to depressed position thereby, said fingers springing to normal position when beyond the rigid fingers in locking cooperation with the rigid fingers.
